(57) **CLAIM**

The ornamental design for a bottle, as shown and described.

DESCRIPTION

FIG. 1 is a perspective view a bottle showing my new design; FIG. 2 is a front elevational view thereof, the right side elevational view, left side elevational view, and rear elevational view being identical except for the unclaimed pour spout portion;

FIG. 3 is a top plan view thereof; and,

FIG. 4 is a bottom plan view thereof.

The portion of the pour spout and thread shown in broken lines in the drawing views is included for the purpose of showing environmental structure that forms no part of the claimed design.
